US00D669113S

(12) **United States Design Patent**
Sandor et al.

(10) **Patent No.:** **US D669,113 S**
(45) **Date of Patent:** **** Oct. 16, 2012**

(54) **SPORTS GOGGLE**

(75) Inventors: **Brent Sandor**, Encinitas, CA (US);
Patrick Bryan Dawley, Encinitas, CA (US)

(73) Assignee: **Spy Optic Inc.**, Carlsbad, CA (US)

(**) Term: **14 Years**

(21) Appl. No.: **29/417,923**

(22) Filed: **Apr. 10, 2012**

(51) LOC (9) Cl. **16-06**

(52) U.S. Cl. **D16/312; D16/309**

(58) **Field of Classification Search** D16/101,
D16/300-342; D29/109-110; D24/110.2;
351/41, 44, 51-52, 62, 158, 92, 103-123,
351/140, 153, 45-46; 2/426-432, 447-449,

Primary Examiner — Raphael Barkai(74) *Attorney, Agent, or Firm* — Stetina Brunda Garred & Brucker(57) **CLAIM**

The ornamental design for a sports goggle, as shown and described.

DESCRIPTION

FIG. 1 is a front perspective view of the sports goggle of the present invention showing our new design with the dotted lines depicting solely environmental structure and forming no part of the claimed design;

FIG. 2 is a front plan view thereof;

FIG. 3 is a right side elevational view thereof;

FIG. 4 is a left side elevational view thereof;

FIG. 5 is a rear elevational view thereof;

FIG. 6 is a top plan view thereof; and,

FIG. 7 is a bottom plan view thereof.
